MOLDED REFLECTOR BUTTON

Thomas H. Morcom, Rochester, N. Y., assignor
to General Railway Signal Company, Rochester,
N. Y.

Application September 30, 1938, Serial No. 232,559

2 Claims. (Cl. 88—82)

The present invention relates, in general, to luminous signs for use along the wayside of railways, highways, and the like, and has more particular reference to reflector buttons of the unit molded type, for use in such signs.

In the manufacture of luminous signs employing reflector buttons which receive light from an outside source, and reflect the light back to the source, it is desirable to provide buttons which are economical to manufacture and which are brilliant and durable and long lived.

With the above and other considerations in mind, it is proposed, in accordance with this invention, to provide a reflector button which is molded in a single operation from a transparent material, with the reflector molded into the button so as to be embedded therein. In producing such buttons it is apparent that the molded material constituting the body of the button must be of a character which can be worked at a low enough temperature to avoid injuring the reflecting surface of the embedded reflector.

More specifically, it is proposed, in accordance with this invention, to employ a reflector of steel, or the like, having a reflecting surface of nickel, chromium, silver, or other suitable material, and to mold this reflector in a transparent material which can be molded at a low enough temperature to avoid tarnishing, or in any way harming, the reflecting qualities of the reflecting surface.

Further objects, purposes and characteristic features of the present invention will appear as the description progresses, reference being made to the accompanying drawing, showing, wholly in a diagrammatic form, and in no manner whatsoever in a limiting sense, two forms of the invention. In the drawing:

Fig. 1 is a fragmentary plan view of a reflecting sign, in accordance with this invention.

Fig. 2 is a sectional view, with parts shown in elevation, on line 2—2 of Fig. 1, and viewed in the direction of the arrows.

Fig. 3 is a sectional view, with parts shown in elevation, and parts broken away, of a mold and its contained button, for producing the button.

Fig. 4 is a sectional view, on line 4—4 of Fig. 3, and viewed in the direction of the arrows.

Fig. 5 is a longitudinal sectional view, on line 5—5 of Fig. 4, and viewed in the direction of the arrows, and with the mold omitted, and to an enlarged scale, of a reflector button, in accordance with this invention.

Fig. 6 is a view, similar to Fig. 3, of a modified form of the invention.

Referring now to the drawing, and first to Fig. 1, there is here shown a portion of a luminous or reflecting sign, constituted by a support, or back ground, plate 1, of metal or other suitable material, on the face of which are depicted characters 2, outlined in any suitable manner. These characters receive reflector buttons B, whereby to make the characters stand out in a luminous manner when light from an approaching vehicle, either a locomotive headlight, or an automobile headlight, or the like, shines upon the buttons B.

The buttons, as shown in section in Fig. 5, are formed with shoulders 3, which bear against the front of support plate 1, and with an annular groove 4 which is spaced the thickness of plate 1 from the shoulder 3, so as to lie to the back of the plate when the reflector button is in place in the plate. This groove 4 is adapted to receive a U-shaped metal clip 5 functioning as a retaining member, which is sprung into place in groove 4, and which is circular in cross section, whereby to project beyond the groove and form a retaining shoulder bearing against the back of plate 1.

The reflector button, as best shown in Fig. 5, has a front refracting surface FS, and a back or inner reflecting surface BS, these two surfaces being suitably spaced from each other so as to produce a button which can be characterized as reflex reflecting, or, in other words, autocollimating. In other words, the button is so formed that light from an external source which is received parallel to the longitudinal axis 6 thereof, or from any direction included within an angle to either side of the axis 6 of about 30°, is refracted by the front surface FS and reflected from the back surfaces BS, to return toward the source of light in a line parallel to the entering beam, although, in some cases, slightly displaced therefrom. This is indicated diagrammatically, by the entering pencil of rays 7, which, after being refracted by the surface FS is reflected from the surface BS and emerges at 8 in a direction parallel to the entering beam 7. All other light beams striking the button substantially within the limits referred to above, emerge in a like manner.

The reflecting surface BS is spherical in form and is constituted by a coating 9, of nickel, silver, chromium, aluminum, or any other suitable material, placed on the inner face of a reflecting plate 10, which is relatively thin and is made of steel, or the like.

Referring to the refracting surface or front surface FS, this surface is formed as a surface of rotation about the axis 6, of the curve as shown in Fig. 5. This curve is constituted by a central

circular portion 13, having a radius 11 of a length of .255 inch; and a center at 12 on the axis 6, and at each side of curve portion 13, is a circular portion 14 and 15, which connects to the portion 13 where the curves become tangent, so that they merge into each other and produce no abrupt change in curvature. These portions 14 and 15 are portions of circles, having centers at 16 and 17 and having radii of lengths of .367 inch. The centers of the curves 14 and 15 are placed to 10 opposite sides of the axis 6, as shown in Fig. 5, and are placed rearwardly along the axis 6 with respect to the center 12 for the central curve 13.

The complete curve, formed as described just above, and constituted by the portions 13, 14 and 15, upon being rotated about the axis 6, forms the front aspherical refracting surface FS, constituting an essential part of this reflecting button.

The axial distance between the reflecting surface BS, and the refracting surface FS, is so chosen as to make the button reflex reflecting for the material employed, and in accordance with the index of refraction of the material employed. With the material to be described below, and having an index of refraction of 1.49, the spacing of these two surfaces, is as shown in the drawing, approximately three times the radius 11 of the front central portion 13 of the front surface FS. To state it mathematically exactly the distance is equal to $760/255$ of this radius 11, or approximately 2.98 times radius 11. Furthermore, it can be noted that the radius for the spherical reflecting surface is approximately two and one-half times the radius 11 for the central portion of the refracting surface and that the centers of curvature of these two surfaces are overlapped to an extent of about one-half the length of radius 11. With this arrangement and proportioning of parts a very perfect autocollimating button is obtained.

In the production of the buttons in accordance with this invention, a mold is employed which can be of the form as shown in Fig. 3, for example. This mold comprises a top portion 18 and a bottom portion constituted by two separate side members 19 and 20, joining along the line 21, and a separate support insert member 22 for the reflector 10. The top member 18 carries pins 23, receivable in openings 24 in the bottom members, for holding the parts in proper position for the molding process.

With the mold as described just above, the reflector is first placed in the mold in the position shown in Fig. 3, and is accurately centered therein by the projecting fingers 25, which are here shown as being three in number and extending outwardly so as to contact with the inner cylindrical side of the mold. The reflector is supported on the portion 22 so as to hold it in position and carry it on a broad enough base to avoid any deformation of the reflector during the molding process.

Material employed in forming the button can be any suitable thermo-plastic material, of a transparent character, which can be molded at a low enough temperature to avoid tarnishing or otherwise harming the reflecting qualities of the reflecting surface 9 or deforming the body 10 of the reflector. While many materials may be produced which are suitable for this purpose, at the present time it has been found that for various reasons, many of the commercially available plastics now on the market are quite unsuited, due to lack of transparency, high working temperatures, poor ageing qualities, etc. One material

which has been found admirably suitable for this purpose is to be obtained under the commercial name of "Crystalite," and the particular type of "Crystalite" which has been used with great success is identified as No. 1 or S. This material is an acrylic resin and is obtainable in a powdered or granular form.

In molding the button in accordance with this invention, after the reflector has been placed in the mold, as described above, the molding material, to a measured quantity, is placed in the mold, and then the mold is closed under a pressure varying from 2000 to 4000 pounds per square inch, while being subjected to a temperature of from 300° to 360° Fahrenheit. With such high pressures employed, it is very essential that the relatively thin reflector 10, be securely supported against displacement in the mold, and against deformation of its contour, and the mold, as described above, performs these functions most satisfactorily.

Also, with material which can be successfully molded at as low a temperature as 360° Fahrenheit, the reflecting surface of the reflector is not tarnished or harmed in any manner whatsoever. While the temperature may vary over the range indicated, it has been found that very satisfactory results have been obtained with the employment of a temperature of 330° Fahrenheit, and with a pressure of 3000 pounds per square inch.

It can be noted that the molded material can pass down beyond the body of the reflector, between the fingers 25, and cover the rear side of the reflector 10 to an extent determined by the portion 22 of the mold, and this portion can be varied in area to some extent, although it must be sufficient to adequately support the reflector against deformation.

After the material has been molded into place, 40 the mold can be taken apart and the button in its complete form, is ready for use. The reflector is embedded in the molded material and completely shielded against any mechanical or chemical change taking place in the reflector, such as 45 deformation, or oxidation in the front face, or the like. The button is therefore very durable and rugged, and secure against harm and destruction, and still is very economical to produce since the entire button is produced by a single molding operation of a very simple nature.

One of the main features which makes possible the production of the buttons in accordance with this invention, is the employment of a plastic material which can be molded at a low temperature so as not to harm or destroy the reflector or the reflecting surface. Another feature which makes the production of this button possible is the employment of a mold so cooperating with the reflector as to permit the reflector to be accurately positioned in the mold without any great difficulty and to permit supporting the reflector so as to avoid deformation under the very high pressures necessarily employed in the operation.

In certain cases, it may be found desirable to somewhat simplify the form of mold employed, at the expense of subsequent machining of the button after it has been molded. More specifically, it may be desirable, from the point of economy, to employ merely a two part mold, and later to machine the groove 4 in the button.

Referring now to Fig. 6, there is here shown a mold wherein the button can be produced as described just above, that is, groove 4 is not formed

in the button during the molding process, but is subsequently machined therein.

The mold of Fig. 6 is comprised of a top member 26, carrying pins 27, fitting into openings 28, in a bottom member 29. The member 29 has a support portion 30, as described above, for the reflector 18, and in this case there is provided an opening 31, for receiving a suitable tool for pushing the button out of the lower portion 29 after the top of the mold has been removed. The button is then machined to form the groove.

A button formed as described in connection with Fig. 6, in its finished form, is exactly the same as that described above in connection with the other figures, but under certain conditions it may be more economical to produce the button in this last described manner.

Summarizing some of the features of the present invention, it can be seen that a button has been produced which is very economical to manufacture and which is very rugged and durable in use. The reflector is embedded within the transparent material forming the body of the button, and this is made possible by the employment of a mold which suitably supports the reflector, and the employment of a material which can be worked at a sufficiently low temperature to avoid any harm to the reflecting surface or body.

Furthermore, this button is very brilliant, when used, due to its optical characteristics, which are, essentially, an aspherical refracting front surface and a spherical reflecting rear surface properly spaced one from the other.

The above rather specific description of two forms of this invention, has been given solely by way of example, and is not intended, in any way whatsoever, in a limiting sense. Various modifications and adaptations can be made, as may occur from time to time to be desirable in practice, without departing from the scope or the spirit of the present invention, except insofar as it is limited by the appended claims.

Having described my invention, I now claim:

1. A reflector button comprising an elongated

body of molded transparent thermo-plastic material moldable at not more than 350° F., and having an index of refraction of about 1.49, an aspherical refracting face on the front of the button having a central spherical portion, a spherical forwardly directed reflecting member molded in the body near the rear of the button, the radius of the reflecting face being about 2½ times the radius of the central portion of the refracting face, the radii of said two spherical portions having their inner ends on the same longitudinal axis and overlapped about ½ the length of the shorter radius, said aspherical face being a surface of rotation of a curve about said longitudinal axis, said curve having a central circular portion the radius of which is said shorter radius, and two end portions, each comprised of a circular arc connected tangentially at one end to one end of the central portion and with radii longer than said shorter radius and with their inner ends at opposite sides of said longitudinal axis.

2. A reflector button comprising an elongated body of molded transparent thermo-plastic material having an index of refraction of about 1.49, an aspherical refracting face on the front of the button having a central spherical portion, a spherical forwardly directed reflecting member molded in the body near the rear of the button, the radius of the reflecting face being about 2½ times the radius of the central portion of the refracting face, the radii of said two spherical portions having their inner ends on the same longitudinal axis and overlapped about ½ the length of the shorter radius, said aspherical face being a surface of rotation of a curve about said longitudinal axis, said curve having a central circular portion the radius of which is said shorter radius, and two end portions, each comprised of a circular arc connected tangentially at one end to one end of the central portion and with radii longer than said shorter radius and with their inner ends at opposite sides of said longitudinal axis.

THOMAS H. MORCOM.
